UNITED STATES PATENT OFFICE

163,160

AUTOMOTIVE MIRROR BRACKET

Arthur I. Appleton, Northbrook, Ill.

Application August 2, 1950, Serial No. 11,539

Term of patent 14 years

(Cl. D14—6)

To all whom it may concern:

Be it known that I, Arthur I. Appleton, a citizen of the United States, residing at Northbrook, in the county of Cook and State of Illinois, have invented a new, original, and ornamental Design for an Automotive Mirror Bracket, of which the following is a specification, reference being had to the accompanying drawing, forming a part thereof.

Fig. 1 is a front elevational view of an automotive mirror bracket embodying my new design;

Figs. 2 and 3 are respective right and left-hand side elevational views, the position of the mirror being indicated in dot-dash outline; and

Fig. 4 is a plan view of the bracket as illustrated in Fig. 1.

In the drawing, a mirror has been shown in dot-dash outline on the bracket for illustrative purposes only.

I claim:

The ornamental design for an automotive mirror bracket, substantially as shown and described.

ARTHUR I. APPLETON.
